UNITED STATES PATENT OFFICE.

SILVIO COCANARI, OF VIEUX-DIEU, BELGIUM.

KINEMATOGRAPHIC FILM.

1,085,724.

Specification of Letters Patent. Patented Feb. 3, 1914.

Application filed September 10, 1912. Serial No. 719,640.

To all whom it may concern:

Be it known that I, SILVIO COCANARI, technologist, a subject of the King of the Belgians, and resident of 152 Chaussée d'Anvers, Vieux-Dieu, Belgium, have invented certain new and useful Improvements in and Relating to Kinematographic Films, of which the following is a specification.

10 My present invention relates to kinematographic films and has for its object to provide an improved method of and devices for enabling films, the width of which is reduced to the width of the prints, and films 15 of any desired width less than the usual films, to be used in ordinary kinematographic machines.

In contradistinction to arrangements heretofore known, my present invention provides means, whereby the film is not directly engaged by the pins of the feed-rollers of the apparatus, but through the agency of a supporting strip the longitudinal rims of which are provided with perforations intended to be engaged by the pins of said feed-rollers, said supporting strip having suitable apertures corresponding to the size of the pictures of the film.

20 A further object of my invention is to provide means, whereby the film and supporting strip are temporarily connected together and firmly pressed upon each other when passing in front of the lens of the kinematographic apparatus.

25 In carrying the invention into practical effect, I preferably form the supporting strip of an endless belt, which is moved through the apparatus in the usual way and detachably connected to the film near the lens of said apparatus, so that the film is caused to pass in front of the lens as usual, whereupon the film is again disengaged from the supporting belt and wound upon the receiving roller in the usual way.

30 It will be seen that my present invention provides means, whereby many objections inherent to the old arrangements may be completely avoided.

The usual films provided with lateral perforations and actuated directly by the pin-rollers of the kinematographic apparatus, do not enable films of any desired width to be used in the same apparatus, and the printed surface of said films is comparatively small, as comparatively large rims must be left on either side for the perforations. In contradistinction to this old arrangement, my present invention enables films of different width to be used in the same apparatus, that is, the width of the films may be reduced to the width of the printed pictures, whereby a great deal of material may be saved. Furthermore, my invention enables old films, the perforated rims of which are worn out or injured, to be used again, said rims being merely cut away to this end, so as to reduce the width of the films to the width of the pictures. I may also use films of any other width, provided that the apertures of the supporting belt correspond to the size of the pictures.

I will now proceed to describe my invention in detail with reference to the accompanying drawings, wherein:

Figure 1 shows a printed film, the width of which is reduced to 25 mm. and a usual film (in dotted lines) of 35 mm. wide; Fig. 2 shows the front elevation of a portion of the supporting strip; Fig. 3 is a vertical section of same; Fig. 4 is a diagrammatical view of a kinematographic lumière apparatus, provided with the endless supporting belt; Fig. 5 shows a supporting belt for narrow films (20 mm. wide); and Fig. 6 shows a film corresponding to the supporting belt shown in Fig. 5. Fig. 7 is a diagrammatical view of a Pathe apparatus provided with the endless belt.

As shown in Fig. 1, the printed film 11 is made of a width A-B, which is equal to the width of a picture 8. Arranged below said films is a film of usual width C-D, and this illustration shows clearly the quantity of material which may be saved by using the film 11 instead of the film C-D. Arranged

between the adjacent pictures of the film 11 on the plain transverse surfaces 7 are perforations 6. The supporting strip 1, shown in Figs. 2 and 3 is made of the same width as the usual films and has perforations 2 on its longitudinal rims. Said strip 1 is provided with apertures 3, corresponding to the size of the pictures printed on the films to be used in connection with the strip 1. The transverse rims 5 between the adjacent apertures carry projecting pins 4, intended to engage the corresponding perforations 6 of the films.

The supporting strip 1, which may be made of sheet steel or any other suitable material, has its ends preferably connected together to form an endless belt. This endless supporting belt may be arranged on any ordinary kinematographic apparatus, as shown in Fig. 4 the arrangement being such that the belt passes over a roller 9 and between a suitable pressing-device 10 and the lens of the apparatus. Said supporting belt is actuated by the usual operating devices of the apparatus. The film 11 is moved in the usual way from the feed roller over a guide-roller to the receiving roller, after passing between the pressing-device 10 and the lens, where the film is firmly pressed upon the supporting belt. At the same time the pins 7 of the latter engage the perforations 6 of the film, so that the film is drawn forwardly by the supporting belt. After the latter and the film are moved beyond the lens, the film will be disengaged from the supporting belt and wound upon the receiving roller in the usual way.

Owing to the use of supporting belts made of strong material such as metal or the like, the apertures or openings of said belts may be made comparatively large, while the transverse solid parts between the adjacent apertures may be made comparatively narrow, whereby films with larger pictures than heretofore may be used. Furthermore the provision of supporting belts of the kind described enables films of reduced width to be used as shown by way of example in Figs. 5 and 6.

The arrangement described has the following advantages: 1. In ordinary kinematographic machines I may use films, the width of which is utilized totally for printing pictures. 2. I may use printed films of different width in the same apparatus. 3. As the whole surface of the films is utilized for printing pictures upon the same, the material will be utilized in the best manner. 4. Owing to the use of a strong supporting belt, the film is prevented from being injured in contradistinction to the usual films, whose longitudinal rims are perforated. 5. I may use old injured films, by cutting away the injured perfor-

rated rims and perforating the plain portions between the adjacent pictures.

What I claim and desire to secure by Letters Patent of the United States is:

1. The combination with a kinematographic machine, of a film whose longitudinal rims are not provided with perforations, a suitable supporting device having perforations at the longitudinal rims and corresponding to the pins of the operating rollers of the machine, said supporting device being provided with apertures corresponding to the pictures printed upon the film and means for temporarily connecting the supporting device and the film, substantially as set forth. 75

2. The combination with a kinematographic machine of a film whose longitudinal rims are not provided with perforations, an endless belt, apertures in said belt corresponding to the pictures printed upon the film, means for moving the belt through the machine, and means for temporarily connecting the belt and film, substantially as set forth. 80

3. The combination with a kinematographic machine, of a film made of the width of the pictures printed upon the same and whose longitudinal rims are not provided with perforations, an endless belt, perforations at the longitudinal rims of the belt and corresponding to the pin-rollers of the machine, apertures in the central portion of said belt and corresponding to the size of the pictures printed upon the film, and means for temporarily connecting the belt and film, substantially as set forth. 90

4. The combination with a kinematographic machine, of a film made of the width of the pictures printed upon the same, an endless belt, perforations at the longitudinal rims of said belt and adapted to coöperate with the driving-rollers of the machines, apertures in the endless belt corresponding to the pictures printed upon the film, means for temporarily connecting the belt and film, and means for firmly pressing the film upon the belt when it is connected with the latter, substantially as set forth. 105

5. The combination with a kinematographic machine, of a film made of the width of the pictures printed upon the same, perforations between the adjacent pictures of said film, an endless belt, means for moving said belt, through the machine, apertures in the belt corresponding to the pictures of the film, and projecting pins between said apertures adapted to engage the perforations of the film near the lens of the machine, substantially as set forth. 115

6. The combination with a kinematographic machine, of a film made of the width of the pictures printed upon the same, perforations between the adjacent pictures

of said film, an endless belt, means for moving said belt through the machine, apertures in the belt corresponding to the pictures of the film, projecting pins between said apertures adapted to engage the perforations of the film near the lens of the machine, and means for securely holding said pins in engagement with said perforations when the belt and film are moved together in front of the lens, substantially as set forth.

In witness whereof I have hereunto set my hand in the presence of two witnesses.

SILVIO COCANARI.
